CLAIM

The ornamental design of a switcher control head as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a right, upper, front perspective view of a switcher control head;

FIG. 2 is a right, lower, rear perspective view thereof;

FIG. 3 is a front, elevation view thereof;

FIG. 4 is a back, elevation view thereof;

FIG. 5 is a left, elevation view thereof;

FIG. 6 is a right, elevation view thereof;

FIG. 7 is a top, elevation view thereof; and,

FIG. 8 is a bottom, elevation view thereof.

The broken lines in the drawings are illustrative of the environment and form no part of the claimed design.

1 Claim, 8 Drawing Sheets
